UNITED STATES PATENT OFFICE.

ISAAC RUBEL, OF CHICAGO, ILLINOIS.

RANGE.

SPECIFICATION forming part of Letters Patent No. 445,289, dated January 27, 1891.

Application filed September 2, 1890. Serial No. 363,764. (No model.)

To all whom it may concern:

Be it known that I, ISAAC RUBEL, a citizen of the United States, residing at Chicago, Illinois, have invented certain new and useful Improvements in Ranges, of which the following is a specification.

The object of my invention is to make a range for cooking, in which there are two chambers or ovens, which may both be used as baking-chambers, or one used interchangeably as a baking and warming chamber, as may be desired; and my invention consists in the features and details of construction hereinafter described and claimed.

In the drawings, Figure 1 is a vertical section taken through the range from front to rear. Fig. 2 is a vertical section taken through the line 2 of Fig. 1, looking in the direction of the arrow; and Fig. 3 is a side elevation of a sliding damper hereinafter described.

In making my improved range I make it with a fire-box A, and with a baking-chamber or oven B and a warming-chamber or oven C, much in the usual way. I leave a space between the two chambers, as shown in the drawings. I arrange in this space a vertical partition D, that begins about the center of the flue E, which is located, as usual, at one side of the range, and carry it diagonally back toward the rear of the opposite side of the range, but not far enough to reach it. In other words, I arrange a vertical partition in the space between the chambers B and C, inclining back from about the middle of the flue to a desired distance, so as to leave a space between the end of the partition and the side of the range opposite the flue. By beginning the partition about midway of the flue a passage to the flue is secured both in the front and in the rear of the partition, which I will term the "front" and "rear" passages to the flue.

I arrange a sliding damper F, provided with an open space G, in suitable guides to permit it to be slid back and forth at the entrance of the flue, so as to respectively close or open the passage to the flue in the front or in the rear of the partition. When the damper is moved forward, as shown in the drawings, it closes the passage to the flue in front of the partition, but leaves the passage in the rear of the partition open, and when it is moved

back it opens the passage in front of the partition and closes the passage in its rear. In this way I can have one or the other of the 55 passages open, as may be desired.

A rod H extends from the sliding damper to the back of the range to permit the damper to be adjusted back and forth. This rod also may be used to manipulate a damper I, arranged at the back of the space between the two chambers B and C, and open and close it in unison with the movements of the damper F. When the rod is pushed in to slide the damper F into its forward position to close 65 the passage to the flue in front of the partition D, the damper I is also moved forward to close the rear end of the space between the chambers B and C, and when it is drawn back to open such passage the damper I is moved 70 back to open the rear end of the space and to close the space J, which leads from the fire-box around the chambers. When the damper I is moved forward, the heat from the fire-box can pass around back of both the chambers 75 and down under and up in front of the chamber C; but when it is moved back the heat is prevented from passing down under and around the chamber C and is deflected into the space between the two chambers. A damper K is 80 also provided in the flue near the top of the range to secure a direct draft up the flue when desired.

In operation and with the damper K closed the heat from the fire-box passes along the 85 space J above the chamber B and down the back of the chamber. If the rod H be moved forward and the rear of the space between the chambers closed, and the front passage to the flue be closed and the rear passage to the 90 flue be opened, the heat will pass on down back of the chamber C and then forward under the chamber and up in front of it and enter the space between the two chambers. As the front passage to the flue is closed, the heat 95 passes diagonally back along the inclined partition, thus crossing the chambers toward the side opposite the flue, and then turns around the end of the partition and back across the chambers to the rear passage to the 100 flue. In this way both chambers are fully subjected to the action of the heat and converted into baking-chambers. If, however, the rod H be drawn back and the rear end of

the space between the chambers closed, and also the space J behind the chamber C, and the rear passage to the flue closed and the front passage to the flue opened, the heat enters the space between the two chambers and passes around the end of the partition and out through the front passage of the flue. In this way the chamber B only is sufficiently heated to form a baking-chamber, and the chamber C is simply employed as a warming-chamber. I am thus able to use both chambers as baking-chambers or to use one of them as a baking-chamber convertible into a warming-chamber, as circumstances may render necessary or desirable.

What I regard as new, and desire to secure by Letters Patent, is—

1. In a range, the combination of two chambers, one above the other and provided with

a space between them, a partition extending 20 from about the middle of the flue back diagonally across the space to a point short of the side of the range opposite the flue, and a sliding damper to alternately open and close the front and rear passages to the flue, substantially as described.

2. In a range, the combination of an upper chamber and a lower chamber provided with a space leading from the fire-box above the upper chamber, behind both chambers, under 30 the lower chamber, in front of the lower chamber, and between the two chambers, substantially as described.

ISAAC RUBEL.
